UNITED STATES PATENT OFFICE.

JULIUS BRENZINGER, OF FAIRFIELD, AND PAUL H. LANGE, OF BRIDGEPORT, CONNECTICUT, ASSIGNORS TO THE MAX AMS MACHINE COMPANY, OF BRIDGEPORT, CONNECTICUT, A CORPORATION OF NEW YORK.

EJECTING MECHANISM FOR HOLLOW BODIES.

Application filed November 22, 1922. Serial No. 602,506.

To all whom it may concern:

Be it known that we, JULIUS BRENZINGER and PAUL H. LANGE, citizens of the United States, and the former a resident of Fairfield, in the county of Fairfield and State of Connecticut, and the latter a resident of Bridgeport, in the county of Fairfield and State of Connecticut, have invented certain new and useful Improvements in Ejecting Mechanism for Hollow Bodies, of which the following is a specification.

This invention relates generally to heading machines, and has for its main object and feature the detection of the absence of a cover from position on a body or container and the consequent removal of the body from the machine. If such absence is not detected and the body is not removed the body continues through the machine and the seaming operation is performed thereby spoiling said body.

In the accompanying drawings the invention is disclosed in a concrete and preferred form in which

Fig. 1 is a front elevation of a heading machine and associated parts embodying the invention.

Fig. 2 is a plan view on the plane of line 2—2 of Fig. 1.

Fig. 3 is an enlarged plan view of the parts in upper left hand corner of Fig. 2 showing the position of the parts when a cover is in place on the body.

Fig. 4 is a vertical sectional view on the plane of line 4—4 of Fig. 3.

Fig. 5 is a side elevation looking in the direction of arrow 5 of Fig. 4 with the ejector cam in section and with parts broken away.

Fig. 6 is a plan view on the plane of line 6—6 of Fig. 7 showing the ejector means in the act of removing a container or body from the machine.

Fig. 7 is a front elevation of Fig. 6 with the turret in section.

The heading machine structure itself may be of any suitable character such as the well-known Max Ams heading machine. The in-feed and out-feed means may likewise be of any suitable construction but are preferably of the character disclosed in applica-

tion Ser. No. 602,505 filed November 22, 1922.

In its general construction the machine here comprises a step-by-step rotatable turret 1 having pockets 2 which slide the bodies over table 3 and thus move said bodies in an orbit through the machine from in-feeding station 4, to ejector station 5, to seaming station 6 and to discharge station 7. In the present instance the bodies intended to be acted upon are square or non-round oblong bodies 8 and are fed into the machine in a recumbent position by in-feed means 9. They are then up-ended by means of spider 10, after which pusher 11 moves the bodies into pockets 2 of the turret. After a body has traversed the orbit it is removed from pocket 2 at station 7 by discharge means 13 which eventually push it on out-feed 70 means 12.

Located adjacent to ejector station 5 are the following means. 14 indicates a stationary support carrying an upright guide member 15, said support having bushings 16, 17, 18 and 19 arranged in two pairs, an upper and lower one, the members of each pair being connected by a webbing 20, as shown. Slidably mounted in this support are two vertical reciprocating rods 21 and 22 which are seated respectively in bushings 16 and 18 and 17 and 19. Mounted fast on rod 21 is a bracket 23 which has a bushing 24 slidably engaging vertical guide member 15 and mounted fast on rod 22 is a detector 85 which consists of a bushing 25 carrying an arm 26 at the outer end of which is pivotally mounted a lever 27 normally held at right angles to arm 26 by means of spring 28 but capable of yielding in a manner presently to be described. One end of the lever 27 carries detector finger 28 which is in the form of a downwardly projecting rod. Mounted fast on rod 22 is a sleeve 29 that carries an arm 30 provided with a sleeve 95 31 slidably and loosely engaging vertical guide 15. Any suitable means may be provided for vertically reciprocating rod 21, in this instance consisting of cam 32 which actuates bell crank 33 pivoted at 34 and to 100 which is pivotally connected links 35 which latter are also pivotally connected with rod

21. It will be understood from the foregoing that the vertical reciprocation of rod 21 effects a like movement of bracket 23 and bushing 24 and that on a downward movement of bracket 23 and bushing 24, the detector mechanism will likewise move downward unless otherwise prevented since said detector mechanism is sustained by bushing 24 and that an upward movement of bracket 23 and bushing 24 will raise the detector mechanism. Rod 22 is a rockshaft and carries at its upper end an extension 36 on which is supported a downwardly projecting member 37 extending through arcuate slot 38' in webbing 20. Mounted loosely on rod 21 is a sleeve 38 carrying two members 39 and 40. These members 39 and 40 together with sleeve 38 are oscillated in a horizontal plane by any suitable means, in the present instance taking the following form. 41 indicates a cam actuating bell crank 42 pivoted at 34, the motion of said bell crank 42 being imparted to another bell crank 43 pivoted at center 44 by means of connection 45. Bell crank 43 is connected with arm 46 of sleeve 38 by means of links 47 whereby an oscillating motion is imparted to sleeve 38 and members 39 and 40.

The parts are so timed that as a container 8 comes in position at the ejecting station, bracket 23 and bushing 24 will descend thereby also allowing the detector mechanism to descend. If there is no cover on the container or body, then detector finger 28 will be permitted to project into said body and by this movement will carry rockshaft 22 and member 37 with it. Member 37 will thereby be brought into the plane of the oscillating arms 39 and 40 and by this time sleeve 38 is given a motion in such a direction as to cause arm 40 to engage member 37 and thereby cause rockshaft 22 to turn in its bearings; and this, in consequence, imparts an oscillating motion to detector finger 28 thereby sweeping the body or container out of pocket 2 and down incline 49 of table 3. The parts now return to their original positions, bracket 23 rising and arm 39 engaging with member 37 to turn, in the reverse direction, rockshaft 22 which carries with it the detector mechanism. If upon the inward movement of the detector mechanism toward the turret any portion of said turret should engage with the detector mechanism, lever 27 will yield in opposition to the action of spring 28' and as soon as clearance between the parts is produced said spring 28' will restore lever 27 to its original position. If, during the next cycle of the machine, a cover, as 48, is in position on the body or container, it will be understood that while rod 21, bracket 23 and bushing 24 will complete their downward descent, said cover 48 will not permit detector finger 28 to descend

within the body 8. In consequence of this, member 37 will not descend into the plane of arm 40 on oscillation of sleeve 38 and hence, when said sleeve is oscillated by the cam movement, its motion will not be transmitted to rockshaft 22 nor to detector 28 with the result that the container remains in position within pocket 2.

We claim:

1. Ejecting mechanism for hollow bodies comprising: an upright rockshaft capable of an up-and-down movement, a detector member carried by said rockshaft to prevent downward movement of the rockshaft beyond a certain point when said detector member encounters a cover on a hollow body and to project within said hollow body when a cover is absent, reciprocating means which on its upstroke raises said rockshaft and which on its downstroke admits of the lowering of said rockshaft, and means for turning the rockshaft effective only when the detector member projects within the hollow body and permits the rockshaft to descend into the plane of said turning means. 90

2. Ejecting mechanism for hollow bodies comprising: an upright rockshaft capable of an up-and-down movement, a detector member carried by said rockshaft to prevent downward movement of the rockshaft beyond a certain point when said detector member encounters a cover on a hollow body and to project within said hollow body when a cover is absent, a vertical guide, a bushing carried by said rockshaft and sliding on said guide, reciprocating means having a member which on its upstroke encounters said bushing and raises it and thereby the rockshaft and which on its downstroke admits of the lowering of said bushing and rockshaft, and means for turning the rockshaft effective only when the detector member projects within the hollow body and permits the rockshaft to descend into the plane of said turning means. 100

3. Ejecting mechanism for hollow bodies comprising: a vertically reciprocating member, two oscillatory arms mounted loosely on said reciprocating member, means for reciprocating said member and for oscillating said arms at timed intervals, an upright rockshaft capable of an up-and-down movement, a member carried by the rockshaft to be engaged by the oscillatory arms, means carried by the upright reciprocating member which on its upstroke raises said rockshaft and the member carried thereby above the plane of at least one of the oscillatory arms and which on its downstroke admits of the lowering of said rockshaft and the member carried thereby into the plane of both of the oscillatory arms, and a detector member carried by the rockshaft to prevent downward movement of the rockshaft and of the member carried thereby into the 110

115

120

125

plane of both of the oscillatory arms when said detector member encounters a cover on a hollow body, and to project into said hollow body when a cover is absent thereby admitting of the lowering of the rockshaft and of the member carried thereby into the plane of both of said oscillatory arms which

latter thereafter impart a rocking movement to the rockshaft.

Signed at Bridgeport in the county of 10
Fairfield and State of Connecticut this 17th
day of November 1922.

JULIUS BRENZINGER.

PAUL H. LANGE.
